UNITED STATES PATENT OFFICE

GARDNER E. WHEELER AND CHARLES OPPE, OF NEW HAVEN, CONNECTICUT

VEHICLE ARM OR PROP

Application filed December 27, 1927. Serial No. 242,578.

This invention relates to vehicle arms or props, and more particularly to a hinged vehicle arm adapted to support a foldable top for an automobile or the like.

5 Certain types of automobiles and other vehicles are provided with tops which may be kept down in mild weather and erected during inclement weather. These tops are usually supported on bows pivotally secured to the body of the vehicle and are provided with stretchers or props which are connected to the bows and serve to hold the latter securely in place when the top is erected. In order that the top may be 10 readily foldable it is the usual practice to provide props in the form of pairs of hinged arms each of which is connected at one end to the body of the vehicle and at the other end to one of the bows or some other 15 suitable portion of the framework of the top. The present invention relates in particular to a prop of this type.

According to the usual practice the arms of the prop are cast or forged in solid metal, 20 are hingedly connected together and have openings at their outer ends through which pins or bolts may pass to connect the prop to the vehicle body and top respectively. These props are ornamented in various ways, 25 one of the most common practices being to apply a coating of nickel plate to the outer surfaces. When so treated it is highly desirable to provide props made of a non-ferrous metal in order that the nickel plating 30 may not be destroyed by the rusting of the surfaces on which it is applied, it being well known that thin layers of nickel in the form of plating are porous to a considerable extent. It is the usual practice, 35 especially where nickel or other plating is to be applied to make the props out of brass or bronze which may be readily coated with nickel by the electroplating processes and 40 which may be polished to a high degree. However, brass and bronze are both rather expensive metals and as one of the primary objects of our invention we contemplate a prop which may be made of brass or bronze 45 and which while having the outward ap-

pearance of the usual solid prop is much cheaper to manufacture.

In a more specific aspect we contemplate a form of prop for a vehicle top which is made hollow, at least in part, in order not only to reduce the cost of the prop when it is made of brass or bronze, or similar metals, which are fairly expensive, but also to provide a prop, which while having the necessary strength and rigidity, is much 55 lighter in weight than the usual prop. 60

The hinged portions of the prop contemplated are preferably to be made of solid metal, and a further object of the invention resides in a novel means for connecting the tubular portions of the prop to the hinged 65 portions thereof.

An additional object of the invention resides in a novel method of forming the solid hinge portions of the prop and connecting 70 the tubular portions thereto.

To these and other ends, the invention consists in the novel features and combination of parts to be hereinafter set forth and claimed. 75

In the drawings:

Fig. 1 is a plan view of a prop according to our invention;

Fig. 2 is a side elevation of the prop shown in Fig. 1;

Fig. 3 is a sectional view along line 3—3 of Fig. 1;

Fig. 4 is a sectional view along line 4—4 of Fig. 1;

Fig. 5 is a sectional view along line 5—5 of Fig. 1;

Fig. 6 is a sectional view along line 6—6 of Fig. 1;

Fig. 7 is a fragmentary view of one of the hinge portions of the prop;

Fig. 8 is a sectional view along line 8—8 of Fig. 7; and

Fig. 9 is a sectional view along line 9—9 of Fig. 1.

Referring to the drawings in which we have illustrated our invention by showing a preferred embodiment of the same, the reference numeral 10 indicates in general our improved prop which in the embodiment shown is generally of S shape and comprises 95 100

a pair of substantially identical hinge arms 11 and 12 which are for the most part substantially rectangular in cross-section, as shown in Fig. 4, and provided at the adjacent ends thereof with overlapping face plates 13 and 14, which are generally circular in form and of a thickness substantially equal to one half the thickness of the arms 11 and 12. The face plates 13 and 14 are offset to one side of their respective arms and have registering openings 15, through which pass a hinge pin or rivet 16, the outer ends of which are upset into countersunk portions 17 and 18 of washers 19 and 20 bearing against the outer faces of face plates 13 and 14 respectively. Arms 11 and 12 are provided with shoulders 21 and 22 which limit the movement of the arms about the hinge pin 16.

The opposite ends of arms 11 and 12 are provided with integrally formed shanks 23 and 24 which are substantially elliptical in cross-section and on which are received tubular arms 25 and 26, the arms 25 and 26 being substantially straight where they are received on shanks 23 and 24, but curving oppositely to one another where they extend outwardly from the shanks. At their outer ends the tubular arms 25 and 26 are provided with openings 27 (Fig. 9), through which pass hollow rivets 28 having received on the ends thereof on opposite sides of the arms 25 and 26, hollow cup-shaped washers or end caps 29 and 30, these caps closely embracing the adjacent portions of the arms 25 and 26 and the ends of the rivets 28 being turned over to secure the washers to the arms.

The arms 11 and 12 are provided with integrally formed portions 31, 32, and 33, 34 respectively which extend in the direction of and overlie the outer surfaces of the tubular arms 25 and 26. These portions of the arms 11 and 12 may be soldered to the arms 25 and 26, and it is also preferred to solder the ends of the tubular arms 25 and 26 to the arms 11 and 12 at the joints formed between these arms.

In carrying out the invention the hinge arms 11 and 12 may be cast or forged, and the shanks 23 and 24, as well as the portions 31, 32, 33 and 34 formed integrally therewith. The metal between the portions 31, 32, 33 and 34 and the shanks 23 and 24 may be removed in any suitable manner, as for example by means of a saw, whereby these parts are spaced apart to provide sockets for the reception of the sides of the end portions of the tubular arms 25 and 26, the appearance of the arms 11 and 12 after the removal of this metal being shown in Fig. 8. The provision of these portions 31, 32, 33 and 34 not only enhances the appearance of the prop but assists the shanks 23 and 24 in properly supporting the tubular arms 25

and 26 on the hinge arms 11 and 12 by extending over the outer surfaces thereof and providing comparatively large surface areas for the solder to adhere to when the parts are connected together thereby.

It will be readily understood from the foregoing description of the invention that considerably less metal is required in the manufacture of our prop than in the usual form, resulting in great saving in the cost of production of the prop without sacrificing the strength of the prop or destroying the normal appearance thereof. The shape of the shanks on the hinge arms is such that the tubular arms are prevented from turning thereon, resulting in a prop having great rigidity.

While we have described a preferred embodiment of our invention, it is to be understood that the same is not to be limited to all the details shown but is capable of modification and variation within the spirit of the invention and the scope of the appended claim.

What we claim is:

In a vehicle prop, a pair of substantially solid arms hingedly connected together, shanks on said arms, said shanks being generally elliptical in cross-section, extensions on the opposite sides of the solid portions of said arms, said extensions being parallel to the major axes of the generally elliptical shanks and spaced therefrom, and relatively thin walled tubular members shaped to fit and tightly received on said shanks, the extensions and shanks cooperating to form sockets in which the ends of the tubular members are received.

In witness whereof, we have hereunto set our hands this 23rd day of December, 1927.

GARDNER E. WHEELER.
